UNITED STATES PATENT OFFICE.

OTTO B. KIBELE, OF LOS ANGELES, CALIFORNIA.

ROTARY WELL-BORING PIPE COUPLING.

Application filed March 1, 1922. Serial No. 540,331.

To all whom it may concern:

Be it known that I, OTTO B. KIBELE, a citizen of the United States, residing at Los Angeles, in the county of Los Angeles and State of California, have invented new and useful Improvements in Rotary Well-Boring Pipe Couplings, of which the following is a specification.

My invention relates generally to well 10 boring apparatus, and more particularly to an improved coupling for the tube or casing sections that extend downwardly into the well and which coupling may also be utilized between a boring pipe section and 15 the socket member that carries the rotary cutting tool.

My present invention is an improvement upon the coupling that forms the subject matter of my application for patent filed 20 March 2, 1921, Serial No. 449,178, and the principal objects of my present invention are to generally improve upon and simplify the construction of the coupling disclosed in my application aforesaid as well as other 25 similar types of couplings, to provide a coupling that may be easily and quickly applied to sections of tubing, to provide a coupling member having portions that overlap the engaged tube section or casing so as 30 to provide a strong and substantial joint between the connected members, and further to provide a coupling that provides a strong and substantial joint between tube or casing sections or between a tube or casing 35 member and a tool receiving member or socket.

With the foregoing and other objects in view, my invention consists in certain novel features of construction and arrangement of 40 parts that will be hereinafter more fully described and claimed and illustrated in the accompanying drawings, in which—

Fig. 1 is a vertical section taken lengthwise through the center of a coupling of my 45 improved construction and showing the same applied to the adjacent ends of a pair of tube or casing sections.

Fig. 2 is a horizontal section taken approximately on the line 2—2 of Fig. 1.

Fig. 3 is a vertical section taken lengthwise through a coupling member of the type that is utilized for the attachment of a drill or cutting tool to a tube or casing section.

Fig. 4 is a cross section taken on the line 55 4—4 of Fig. 3.

Referring by numerals to the accompanying drawings and particularly to the form of coupling illustrated in Figs. 1 and 2, 10 designates a main body portion of the coupling member, the same being substantially 60 cylindrical in form and its external diameter being practically the same as the external diameter of the tube or casing sections that are to be united by the coupling.

Formed integral with the ends of the body 65 10 are extensions 11, the external diameters of which are less than the diameter of the body 10 and the external surfaces of said extensions 11 are provided with circumferentially disposed ribs or grooves 12, the 70 outer edges of which are adapted to engage the inner surfaces of the casing or tube sections that are joined by the coupling.

Formed through body 10 and its extensions 11 is an axially disposed bore or passageway 13, the end portions 14 thereof being tapered outwardly and communicating with the interior of the casing or tube sections that are connected by the coupling. The shoulders 15 that are formed between 80 the body 10 and the extensions 11 of smaller diameter are inclined or beveled, the arrangement being such that annular undercut grooves are provided for the reception of the ends of the casing or tube sections 16 85 that are joined by the coupling, and in order to provide a snug fit between the parts at these shoulders or under cut grooves the ends of the tube or casing sections 16 are inclined or beveled to correspond with the 90 inclination of the faces of the undercut grooves.

In assembling the coupling the casing or tube sections 16 are driven onto the end portions 11 of the coupling member 10 95 until the ends of said sections fit snugly within the under cut grooves between the body 10 of the coupling and the reduced end portions 11, after which the casing or tube sections are rigidly secured to the 100 tubular end portions 11 by spot welding through the overlapping portions of said tube or casing sections and the tubular end portions 11. When the tube or casing sections 16 are driven onto the tubular extensions 11 the annular ribs or corrugations on the peripheral surfaces of the latter engage the inner surfaces of the tube or casing sections and materially assist in retaining the parts in assembled relation. 105

When the coupling has been properly applied to the adjacent ends of a pair of casing or tube sections a very strong and substantial joint is produced and there are no external shoulders formed adjacent to the joint to interfere with the free movement of the connected tube or casing sections as they are lowered onto or raised from the well hole.

10 In the modified construction illustrated in Fig. 3 the coupling body 18 is provided at its lower end with a depending externally threaded tapered cylindrical member 19 that is adapted to receive the internally threaded upper end of a tool such as a drill or a rotary cutter, and formed integral with the upper end of the body 18 is an axially disposed cylindrical extension 20 that is adapted to be inserted in the lower portion of a tube or casing member 21. The periphery of this extension 20 is ribbed or corrugated circumferentially in order that the coupling member may be firmly secured to the tube or casing section. If desired, 25 this form of coupling may be rigidly fixed to the tube or casing section by spot welding.

In this form of coupling the body 18 is slightly larger in diameter than the diameter of the tube or casing section 21 and formed on the upper marginal edge of the body 18 is an upstanding annular flange 22 and which latter provides between it and

the lower portion of the body of extension 20 an annular channel 23 within which fits 35 snugly the lower end of the tube or casing section 21 when the parts are properly assembled.

Formed through body 18, depending extension 19 and extension 20 is an axially 40 disposed bore or passageway 24.

A tube or casing coupling of my improved construction is comparatively simple, may be easily and cheaply produced, is capable of being easily and quickly connected or disconnected, and is very effective in performing its intended functions.

It will be understood that minor changes in the size, form and construction of the various parts of my tube or casing coupling may be made and substituted for those herein shown and described without departing from the spirit of my invention, the scope of which is set forth in the appended claim.

55 I claim as my invention:

A pipe coupling, including a tubular body having a reduced end which is roughened, the body having an under cut shoulder at the reduced part, to receive an applied pipe end, and a pipe having an internally roughened end and being spot welded on the coupling end.

60 In testimony whereof I have signed my name to this specification.

O. B. KIBELE.
